UNITED STATES PATENT OFFICE.

CHARLES C. BEAM, OF CUMBERLAND, MARYLAND.

DESIGN FOR A PITCHER OR SIMILAR ARTICLE.

Application filed January 18, 1928. Serial No. 24,912. Term of patent 14 years.

To all whom it may concern:

Be it known that I, CHARLES C. BEAM, a citizen of the United States, residing at Cumberland, in the county of Allegany and State of Maryland, have invented a new, original, and ornamental Design for a Pitcher or Similar Article, of which the following is a specification, reference being had to the accompanying drawing, forming part thereof.

The figure is a perspective view of a pitcher or similar article showing my new design.

I claim:—

The ornamental design for a pitcher or similar article as shown.

CHARLES C. BEAM.
